ABSTRACT OF THE DISCLOSURE

A handle for a carrying case, luggage and the like which is collapsible from a raised position above a well in the case to a non-carrying position into the well including a handgrip approximating the size of the well, pivotally interconnected pairs of upper and lower links, means pivoting the upper links to the handgrip, means pivotally securing the lower links in the well automatically in their proper position, and means so limiting the extended position of the links wherein the handgrip is in its raised carrying position so that when the handgrip is released it will return to its non-carrying position and center itself in the well.

This is a continuation-in-part of my copending application Ser. No. 630,389 filed Apr. 12, 1967.

This invention relates to a collapsible handle of the type which is mounted to collapse into a well in a carrying case when released to assume an esthetic non-carrying position and which can be raised so that the handgrip is above and outside the well to a carrying position by exertion of a push downwardly on one end of the handgrip and slipping the hand under the handgrip to pull it up. The mounting means includes articulated pairs of links which are pre-assembled with the handgrip and the hinge brackets for attachment in the well. Because of this and the fact that the handgrip approximates the dimensions of the well, after one hinge bracket is attached to the bottom of the well, the handgrip blocks the view into the well and the second hinge bracket is difficult to attach in proper position.

The primary object of this invention is to provide a construction with a special mounting means which overcomes this disadvantage.

Another object is to provide a collapsible handle of the character described having means preventing the pairs of articulated links from aligning with each other in their extended position when the handgrip is raised, i.e. assuming an angle of 180° or more, so that when the handgrip is released it will fall to the collapsed position automatically.

Another object of the invention is to provide a collapsible handle of the character described in which the pairs of articulated links not only attain included angles between them of less than 180° when extended but also include means to prevent the links pivoted to the case within the well from attaining included angles of 90° or less so that the handle is self-centering when released in that the handgrip cannot shift to one side or the other relative to the well.

Another object of the invention is to provide a collapsible handle which is relatively simple in construction, easy to assemble, attractive and sturdy.

These and other objects of the invention will become more apparent as the following description proceeds in conjunction with the accompanying drawings wherein:

FIG. 1 is a fragmentary perspective view of the handle shown in its collapsed non-carrying position;

2

FIG. 2 is a sectional view taken on the line 2—2 of FIG. 1;

FIG. 3 is a group sectional view similar to FIG. 2 illustrating the raised carrying position;

5 FIG. 4 is a fragmentary enlarged view, some parts in section, of one pair of links shown in the fully extended position;

FIG. 5 is a sectional view taken on the line 5—5 of FIG. 4; and

10 FIG. 6 is a sectional view taken on the line 6—6 of FIG. 4.

Specific reference is now being made to the drawings wherein similar reference characters are used for corresponding elements throughout.

15 The carrying case 10, which is merely illustrative, has an upper wall 12, a well 14 opening therethrough, and a lower wall 16. The handle has a handgrip 18 molded or otherwise fabricated of a suitable plastic such as high heat, high impact polystyrene and which approximates but is somewhat less in length and width than that of the well and is so connected to the carrying case as will soon appear, that it collapses into the well with its upper surface lying substantially flush with that of the upper wall 12 as shown in FIG. 1, and when it is in its raised position, the handgrip is spaced a sufficient distance above the wall 12 as shown in FIG. 3 to permit the same to be gripped for carrying purposes. The handgrip has a bottom surface 20 and recesses 22 adjacent its ends opening therethrough.

20 Adjacent the inner ends of the recesses the handgrip carries cross pins 24 and 26 which pivotally mount the upper ends of upper links 28 and 30, the latter being preferably of channel construction and include laterally spaced apertured ears 32 to journal the cross pins.

25 The lower ends of each of the upper links 28 and 30 are also formed with laterally spaced ears 34 that are received between laterally spaced ears 36 at the upper ends of the sides of lower channel links 38 and 40, there being lateral pins or rivets 42 and 44 which pivotally interconnect the upper links with the lower links respectively.

30 An elongated member 46 is provided in the form preferably of a channel bar having side flanges 48 joined by a web 50 carrying staked-in depending spaced screws 52 and 54. The lower or bottom wall 16 of the well is provided with holes or apertures 56 and 58 spaced conformably to the screws 52 and 54.

35 The lower end portions 60 of the side flanges of the lower links 38 and 40 are apertured and are received between the side flanges 48 adjacent the ends of the bar 46, there being double headed rivets 62 and 64 carried by the side flanges 48 and extending through the apertured portions 60 to serve as pivot pins. The lower edges of the lower end portions 60 of the lower links are angulated as at 66 for a purpose soon to appear. The distance between the pivot pins 62 and 64 preferably approximates that between pivot pins 24 and 26.

40 In use the handgrip 18, articulated links 28, 38 and 30, 40 and the elongated bar 46 are pre-assembled and, as shown in FIG. 3, the unit is dropped into the well 14.

45 Since the dimensions of the handgrip approximates those of the well, with very little manipulation, the shanks of the staked-in screws 52 and 54 will find and pass through the holes 56 and 58 in the bottom wall 16 and then closure nuts 68 and 70 are readily screwed home completing the mounting. By pressing on one end of the handgrip, the other end will raise up and then the other hand can be slipped under the grip to raise the same above the wall 12 and into the carrying position shown in FIG. 3.

50 In the fully raised position of the handgrip, it will be seen that the upper and lower links do not align with each other but rather form angles A included between the

upper and lower links in each pair which are less than 180°, preferably 120°. Thus when the handgrip is released, the links will automatically fold, the lower links 38 and 40 outwardly and the upper links 28 and 30 inwardly over them, as shown in FIG. 2, the recesses 22 in the handgrip being dimensioned to confine the upper links in the final collapsed non-carrying position with the upper surface 18 of the handgrip substantially flush with the wall 12. The less than 180° included angle A between the upper and lower links is attained because the upper free edge 72 of each lower link 38, 40 abuts the lower free edge 74 of each upper link 28, 30 in the fully extended position of the links serving as a stop to prevent the links from attaining an included angle A of 180° or more.

It will also be noted that in the fully raised position of the handgrip, the angulated free edges 66 at the lower end portions 60 of the lower links 38 and 40 abut the web 50 of the mounting bar 44 so that the final angle B included between each lower link and the bar exceeds 90°. Thus, when released the handgrip cannot shift lengthwise relative to the well and is therefore self-centering as it collapses into the well to assume the final non-carrying position shown in FIG. 1.

While a preferred embodiment has here been shown and described, it will be understood that skilled artisans may make variations without departing from the spirit of the invention.

I claim:

1. For use with a carrying case having a well in one wall thereof, a self-centering, self-returning collapsible handle comprising an elongated handgrip whose length and width approximates that of said well and having upper and lower surfaces, and means to anchor said handgrip in said well so that when released it will collapse into said well in its non-carrying position with its upper surface substantially flush with said one wall in which said well is provided, said means including pairs of upper and lower links, first means pivotally interconnecting each pair of links, second means pivotally securing said upper links to said handgrip adjacent its ends, an elongated member, means securing said elongated member to the bottom surface of said well, means pivotally securing the lower links to said elongated member adjacent its ends, and means limiting the included angle between each pair of links so that it is less than 180° when said handgrip is raised to its carrying position above said one wall in which said well is provided.

2. The combination of claim 1 and means limiting said lower links when fully raised to included angles greater than 90° between said lower links and said elongated member which is secured to the bottom surface of said well.

3. The combination of claim 1 and recesses in said handgrip opening through the lower surface thereof dimensioned to receive and confine at least said upper links when said handgrip is collapsed and said links fold over each other.

4. The combination of claim 1 wherein said last-named limiting means includes edges at the lower end of each upper link and at the upper end of each lower link which engage to provide an included angle of less than 180° when said links are fully extended and said handgrip is in its raised carrying position.

5. The combination of claim 4 and means limiting said lower links when fully raised to included angles greater than 90° between said lower links and said elongated member which is secured to the bottom surface of said well, said lower links limiting means including angulated surfaces at the lower ends of said lower links adapted to engage said elongated member when said lower links are fully raised.

10 15 6. The combination of claim 5 wherein said elongated member includes screws depending therefrom adjacent its ends and adapted to extend into pre-formed spaced holes through the bottom surface of said well.

7. The combination of claim 6 wherein the distance between the pivot points connecting said lower links to said elongated member approximates that between the pivot points connecting said upper links to said handgrip.

20 25 30 35 8. For use with a carrying case having a well in one wall thereof, a collapsible handle comprising an elongated handgrip and means to anchor said handgrip in said well so that the handgrip will enter said well when the handle is collapsed into its non-carrying position, said means including pairs of upper and lower links, first means pivotally interconnecting each pair of links, second means pivotally securing said upper links to said handgrip, a rigid elongated member having threaded members depending therefrom adjacent its ends and adapted to extend into pre-formed spaced holes through the bottom surface of said well, and means pivotally securing the lower links to said elongated member adjacent its ends.

9. The combination of claim 8, and means limiting the included angle between each pair of links so that it is less than 180° when said handgrip is raised to its carrying position above said one wall in which said well is provided.

40 45 10. The combination of claim 8 wherein the distance between the pivot points connecting said lower links to said elongated member approximates that between the pivot points connecting said upper links to said handgrip.
